UNITED STATES PATENT OFFICE.

THOMAS C. DE LISLE, OF LOS ANGELES, CALIFORNIA.

DISPLAY DEVICE.

Application filed November 14, 1921. Serial No. 514,881.

To all whom it may concern:

Be it known that I, THOMAS C. DE LISLE, a citizen of the United States, residing at Los Angeles, in the county of Los Angeles, 5 State of California, have invented certain new and useful Improvements in Display Devices, of which the following is a specification.

This invention has to do with a device for 10 carrying and displaying rugs, or the like, and it is an object of the invention to provide a simple, effective, improved device of this general character.

The present invention relates to certain 15 improvements in display devices of the general character set forth in Patent No. 1,157,252, entitled "Display device," issued to William C. Phillip and Thomas C. De Lisle on October 19, 1915.

20 A noteworthy feature of this invention is the provision of means for effectively holding and guiding the inner or lower edges of the rugs while they are being handled by the device so that the rugs on the base will 25 be in an even smooth pile.

Another feature of the invention is the provision of an improved arrangement and construction such, for instance, as the arrangement of hanger carriers and chain 30 guides, construction of hangers, construction of catch devices carried by the chains, etc.

The various objects and features of the invention will be best and more fully understood from the following detailed description 35 of a preferred embodiment of the invention throughout which reference is had to the accompanying drawings in which:

Fig. 1 is a rear elevation of the complete device; Fig. 2 is a side elevation thereof, being a view taken as indicated by line 2-2 on Fig. 1; Fig. 3 is an enlarged detail sectional view taken as indicated by line 3-3 on Fig. 1; Fig. 4 is a transverse sectional view of certain of the parts shown in Fig. 3 being a view taken as indicated by line 4-4 on Fig. 3; Fig. 5 is a transverse sectional view of other parts shown in Fig. 3 being a view taken as indicated by line 5-5 on Fig. 3; Fig. 6 is a detail sectional view 45 of one of the hangers being a view taken as indicated by line 6-6 on Fig. 4; and Fig. 7 is an enlarged view showing the manner 50 of supporting the lower end of the chain guides, etc.

In the drawings numeral 10 designates a 55 suitable horizontal base upon which the rugs 11 may be laid or piled to display them. The base 10 is preferably carried by supports 12 so that it is spaced somewhat from the floor. Arranged in co-operative relation 60 with the base 10 is a plurality of curved or arcuate hanger carriers 13, and arranged in connection with, or at, the hanger carriers 13 are curved chain guides 14.

The hanger carriers 13, of which I have 65 shown three equally spaced, curve upwardly and rearwardly from the floor at the forward part of the base 10 and have their upper or inner ends connected to a frame 15 which extends upwardly from the floor 70 back of the platform 10. The frame 15 is somewhat wider than the platform 10 and is braced by brace members 16 located at its ends, as illustrated in the drawings. Each hanger carrier preferably extends straight- 75 upwardly from the floor for a short distance before it curves rearwardly, and is long enough that its inner end portion 13a extends downwardly and rearwardly. The curvature of the several hanger carriers is uniform and equal. In accordance with the preferred form of construction the hanger carriers 13, the frame 15, and the braces 16, 80 are formed of pipe and the connections between the various parts are made by pipe 85 fittings. This particular form of construction is particularly simple, neat and inexpensive.

The outer edge portions 18 of the rugs 11 are detachably slidably connected to the 90 hanger carriers 13 by hangers 19. Each hanger 19 is a yoke-like member having two spaced side parts 20 connected by a curved connecting part 21. Connecting part 21 is preferably curved to conform with the cross 95 sectional curvature of the hanger carrier and is formed with a rounded inner edge 22 to engage the carrier. The hanger 19 is arranged on the carrier 13 so that the carrier is between the inner end portions of the 100 arms 20 and is in engagement with the connecting part 21. A pin 24 extends between the arms 20 immediately outward of the carrier 13 to prevent displacement of the hanger from the carrier and to co-operate 105 with the catch mechanisms hereinafter described. A clamping member 26 is pivotally mounted on the outer part of each arm 20

and is adapted to co-operate with the outer end portion 27 of the arm to grip and hold the edge portion 18 of a rug 11. The arm 20 and clamp member 26 may be formed 5 with flanges 27^a and 28, respectively, and may be pivotally connected by a suitable pivot pin 29. The inner end of the clamping member 26 is formed with two spaced projections 30 and 31 which extend inwardly beyond the pivot pin 29. The projection 30, 10 which is the outer projection, extends somewhat beyond the projection 31. A lever 32 is pivotally mounted on the arm 20 by a pivot pin 33 which is carried by the flanges 15 27^a. The lever 32 has a comparatively long arm 35 which forms an operating handle, and a comparatively short arm 36 which is adapted to engage and cooperate with the projections 30 and 31. The arms 35 and 36 20 of the lever 32 are preferably arranged at right angles to each other as I have illustrated in the drawings. When the arm 36 is positioned to extend outwardly at right angles to the arm 20 it engages the end portion 31 and positively holds the clamp member 26 in the closed position. When the arm 36 is swung from this position in a manner to engage and move the projection 30, it causes the clamp member 26 25 to be positively swung open or out in the direction indicated by the lower arrow in Fig. 6. In the preferred form of construction the handle arm 35 lies flat against the arm 20 when the arm 36 is in position to positively hold the clamp part 26 closed. When 30 it is desired to move the arm 36 to cause opening of the clamp part 26 the arm 35 is swung outwardly in the direction indicated by the lower arrow in Fig. 6. To attach a 35 rug 11 to a hanger 19 the clamp members 26 on the arms of the hanger are opened by swinging the arms 35 of the levers 32 outwardly. The outer edge portion 18 of the rug is then arranged between the end portions 40 of the arms 20 and the clamp members 26 whereupon the clamp members 26 are closed by swinging the arms 35 inwardly until they 45 lie against the arms 20. When the arms 35 are in engagement with the arms 20 the arms 50 36 hold the projections 31 out and thereby hold the clamp members 26 in engagement with the edge portion of the rug. In order to make the clamping means just described particularly effective in holding a rug it is 55 preferred that the rug engaging parts may be formed with inwardly extending prongs or projections 39 to extend into the rugs when the clamp members 26 are set.

In accordance with the present invention 60 the inner edges of the rugs are attached to guides 40 by clips or hangers 41 similar to the hangers 19. The guides 40, of which there is preferably one for each hanger carrier 13, have corner parts 42 curved concentrically with the hanger carriers 13, ver-

tical straight parts 43 extending downwardly from the corner parts parallel with the straight lower end parts of the hanger carriers 13, and straight horizontal parts 44 extending rearwardly from the corner parts. 70 When the rugs are up, as at A in Fig. 2, the hangers 41 holding their inner edges are at the straight horizontal part 44 of the guide 40 and when the rugs are down, as at B in Fig. 2, the hangers 41 holding their inner 75 edges are at the vertical parts 43 of the guides 40. Upon moving the rugs between the positions A and B the hangers 41 holding their inner edges pass around the corner parts 42 of the guides 40. In practice the 80 hanger carriers 13 and guides 40 are spaced so that the rugs 11 carried by the hangers 19 and 41 are tight or straight as I have illustrated in the drawings.

For the purpose of moving the rugs 11 between the positions A and B the invention provides a plurality of chains 45, catch mechanisms 46 for connecting the chains and hangers 19 so that the hangers are moved with the chains, guides 14 for the 85 chains, and means 47 for driving the chains. It is preferred that there be three chains 45, one arranged at or in connection with each hanger carrier 13, and that the guides 14, which carry the chains, be arranged immediately within the carriers 13 and that they be curved so that they conform with the curvature of the hanger carriers 13. In accordance with the invention the guides 14 90 are between the arms 20 of the hangers 19. 100 The guides 14 are preferably channel members faced outwardly and curved to conform with the carriers 13, and are supported at their upper and lower ends by brackets 50 and 51, respectively. The brackets 50 105 and 51 have parts 52 which embrace the carriers 13 and are set in place by set screws 53 carried in the parts 52 to engage the carriers 13. The brackets 50 have side parts 54 between which the ends of the guides 14 are 110 carried, and the side parts 54 are formed with projections 55 which carry shafts 56 on which are mounted sprockets 57. The sprockets 57 guide the chains into and receive the chains from the guides 14. From the sprockets 57 at the upper ends of the guides 14 the chains 45 extend downwardly to drive sprockets 58 mounted on a shaft 59 driven from a reversible motor 60 through a suitable spaced reduction mechanism. From 115 the sprockets 58 the chains extend over idler sprockets 61 from which they extend under the base 10 to the sprockets 57^a at the lower ends of the guides 14. It is preferred that the chains 45 be provided at suitable intervals with rollers 65 so that they will be supported in the guides 14 and will not drag in a manner to offer resistance or to cause excessive wear.

The catch mechanisms 46 are preferably 130

spaced considerable distance apart on the chains 45 and are arranged at corresponding parts of the several chains. Each catch mechanism comprises a frame 66 carried by 5 a link of the chain, two oppositely disposed hook members 67 pivotally carried by the frame 66, and springs 68 for operating the hook members. Each frame 66 may be formed with flanges 69 which carry a pivot 10 pin 70 on which is mounted the two hook members 67. The hook members extend in opposite directions from the pivot pin 70 longitudinally of the chain as clearly illustrated in Fig. 3. The hook members 67 are 15 formed at their outer ends with recesses or notches adapted to catch the rods 24 of the hangers 19 to connect the chains and hangers so that the hangers are moved with the chains. In accordance with the invention 20 the recesses 67^a and body parts 67^b of each hook member are formed or constructed so that its recess will only catch and hold a rod 24 when the hook member is moved in one direction and when no other rod is, in 25 engagement with its body part. The springs 68 are arranged under the hook members to normally yieldingly move and hold them up, or out, so that they will engage and hold a rod. The outward movement 30 of the hook members however, is limited by projections 72 at their inner ends engaging the frames 66. In the particular form of catch mechanism shown in the drawings the hook members are formed or 35 constructed so that the leading one, that is, the one extending in the direction the chain is traveling will be depressed upon being moved into engagement with a rod but will not catch or hold a rod. The shape of this 40 outer end 67 causes the depression and the shape of the recess is such that it would not hold a rod when moved relative to it in this manner even though it should receive it. The outer end 67 of each hook member is 45 inclined so that the hook member will be depressed against the resistance of the spring upon its outer end being moved into engagement with a rod 24. The member will be held depressed as long as there is a 50 rod in engagement with the edge 73 of the body part 67^b.

The trailing hook member 67 of the catch mechanism is depressed against the resistance of its spring 68 by the rods engaging 55 the edge 73 of its body part 74. So long as there is a rod 24 in engagement with the edge 73 of the body part the trailing hook member will remain depressed and will not catch a rod. When the rod or the last of a 60 group of rods leaves the edge 73 it is opposite the recess and the spring 68 moves the hook member out, there being nothing to hold it in, so that the said rod is received and held by the recess. The catch mechanisms being 65 located at corresponding parts of the sev-

eral chains the several hangers carrying a rug will be attached to the chains at the same time so that the rug is effectively and evenly carried by the chains. From the foregoing description it will be understood 70 that when a chain is operating in one direction one of the hook members of a catch mechanism operates to catch a rod and when it is operating in the other direction the other hook member operates to catch a rod. 75 When a hanger at one end of a carrier 13 is caught by a catch mechanism it is carried to the other end of the carrier whereupon it is automatically released due to rods of other hangers and the last mentioned end 80 of the carrier, or to a stop member 80, engaging the end 73 of the hook member holding the rod of the hanger causing it to be depressed and thus moved out of engagement with the rod. In other words the 85 catch mechanisms are automatically released, at the ends of the carrier so that they release the hangers which they are carrying, either by the rods of other hangers or by stops 80 provided for that purpose. 90

From the foregoing description it will be understood how the rugs are carried between the hangers 19 and 41 and can be conveniently and easily moved, between the positions A and B so that the desired one 95 is at the top of the group or pile at B, by suitable operation of the motor 60. For instance, when it is desired to move a rug from position A to position B the motor 60 is operated so that the chains move in 100 the direction indicated by the arrow in Fig. 2 thus causing the catch mechanism on the chains to catch the rods of the hangers 19 carrying the foremost rugs 11 at A so that that rug is carried down in the direction indicated by the arrow in Fig. 2 until it is in a horizontal position at the top of the pile of rugs at B. When the rug has reached the top of the pile at B it is automatically released by the catch mechanisms so that no 110 damage is done even though the motor is allowed to continue to run. If the motor continues to operate the chains all of the rugs at A will, one after another, be moved to B. To move a rug from the group at 115 B to the group at A the motor is reversed or operated in a manner opposite to that just described, causing the rug at the top of the pile at B to be carried upwardly until it has reached the group of rugs at A whereupon it is automatically released and allowed to stay at A. The inner or rear ends of the carriers 13 curve downwardly so that the hangers tend to slide rearwardly and thus stay grouped as illustrated in the 120 drawings.

Having described only a preferred form of my invention I do not wish to limit myself to the particular details hereinabove set forth but wish to reserve to myself any 130

changes and variations that may appear to those skilled in the art or fall within the scope of the following claims.

Having described a preferred form of my 5 invention, I claim:

1. In a device for displaying rugs, or the like, a horizontal base, arcuate carriers extending upwardly and rearwardly from the front of the base, hangers holding the outer 10 edge of a rug and slidably carried by the carriers, hangers holding the inner edge of the rug and guides slidably carrying the last mentioned hangers, the guides and carriers being spaced so that the rug is tight 15 between them and so that the rug rests smoothly on the base when the hangers are at the lower ends of the carriers and guides.
2. In a device for displaying rugs, or the like, a horizontal base, arcuate carriers extending upwardly and rearwardly from the front of the base, hangers holding the outer 20 edge of a rug and slidably carried by the carriers, and means for holding and guiding the inner edge of the rug including, guide members, and hangers attached to the inner 25 edge of the rug and carried by the guide members.
3. In a device for displaying rugs, or the like, a horizontal base, carriers having 30 straight vertical parts at the front of the base and arcuate parts extending upwardly and rearwardly from the straight parts, guides at the rear of the base having straight parts parallel to the straight parts of the carriers 35 and curved parts concentric with the arcuate parts of the carriers, and hangers slidably carried by the carriers and guides and adapted to hold rugs between the carriers and guides.
4. In a device for displaying rugs, or the like, a horizontal base, arcuate carriers extending from the front of the base to points spaced above and at the rear of the base, the rear end portions of the carriers extending rearwardly and downwardly, hangers holding the outer edge of a rug and slidably carried by the carriers, and means for holding and guiding the inner edge of the rug. 45
5. In a device for displaying rugs or the like, a horizontal base, carriers having 50 straight vertical parts at the front of the base and arcuate parts extending rearwardly from the straight parts, to points spaced above and at the rear of the base, the rear portions of said arcuate parts extending rearwardly and downwardly, guides at the rear of the base having straight parts parallel to the straight parts of the carriers and curved parts concentric with the arcuate 55 parts of the carriers, and hangers slidably carried by the carriers and guides and adapted to hold rugs between the carriers and guides. 60
6. In a hanger carrier for holding a rug 65 or the like, an arm, a clamp part pivotally

mounted on the arm to cooperate with it in holding a rug, two projections extending from the clamp part, and a lever pivotally mounted on the arm to be positioned to engage one of the projections to hold the clamp 70 part in cooperative relation with the arm, and to be moved to cooperate with the other projection to move the clamp part out of cooperative relation with the arm.

7. In a device for displaying a rug, or the like, a horizontal base, an arcuate carrier extending upwardly and rearwardly from the base, a hanger carried by the carrier and having two spaced arms extending inwardly 80 from the carrier and connecting to the rug and a connecting part engaging the carrier, a guide parallel with the carrier and between the arms of the hanger, a longitudinally moving flexible member carried by the guide, and means connecting the hanger and 85 flexible member so that the hanger moves with the flexible member.

8. In a device for displaying rugs, or the like, a horizontal base, arcuate carriers extending upwardly and rearwardly from the 90 front of the base, hangers slidably carried by the carriers and adapted to hold the outer edges of rugs, and means for guiding the inner edges of the rugs.

9. In a device for displaying rugs, or the like, a horizontal base, an arcuate carrier extending upwardly and rearwardly from the base, hangers slidably carried by the carrier and adapted to hold the edges of rugs, a flexible member movable in either 100 direction parallel to the carrier, means for moving the flexible member in either direction, and means carried by the flexible member for connecting the hangers and flexible member to move the hangers between the 105 ends of the carrier, said last mentioned means comprising two oppositely arranged hook members one adapted to engage and hold a hanger when the flexible member is moving in one direction and the other adapted to engage and hold a hanger when the flexible member is moving in the other direction, and means for releasing the hangers and hook members upon the hangers reaching 110 the end portions of the carrier. 115

10. In a device for displaying rugs, or the like, a base, an arcuate carrier extending upwardly and rearwardly from the front of the base, a hanger holding the outer edge of the rug and slidably carried by the carrier, a hanger holding the inner edge of the rug, and a guide slidably carrying the last mentioned hanger, the guide and carrier being spaced so that the rug is tight between them and so that the rug rests smoothly on the base when the hangers are at the lower ends of the guide and carrier. 120 125

11. In a device for displaying rugs, or the like, a horizontal base, carriers having straight vertical parts at the front of the 130

base and arcuate parts extending upwardly and rearwardly from the straight parts, guides at the rear of the base having straight parts parallel to the straight parts of the carriers and hangers slidably carried by the carriers and guides and adapted to hold rugs between the carriers and guides.

12. In a device for displaying rugs, or the like, a horizontal base, arcuate carriers extending from the front of the base to points spaced above and at the rear of the base,

the rear end portions of the carriers extending rearwardly and downwardly, and hangers holding the outer edge of a rug and slidably carried by the carriers.

15 In witness that I claim the foregoing I have hereunto subscribed my name this 4th day of November 1921.

THOMAS C. DE LISLE.

Witness:

VIRGINIA BERNINGER.
